UNITED STATES PATENT OFFICE.

EVERET HOLLOWELL, OF KANSAS CITY, KANSAS.

PISTON KICKER.

Application filed February 15, 1928. Serial No. 88,395.

The invention relates to locomotive piston kickers and more particularly to apparatus for removing piston rods from the cross-heads of locomotives.

5 Piston kicker is the usual name applied in railway shops to apparatus for removing piston rods from the cross-heads of locomotives, and the usual piston kicker heretofore employed is secured to the cross-head so as 10 to push against the rear wall of the wristpin hole of the cross-head in one direction and the end of the piston rod in the opposite direction. This method is executed by devices employing wedges, also screws, and 15 hydraulic cylinders or jacks have been devised for the purpose.

All devices that employ the wristpin hole for removing piston rods from the cross-heads of locomotives are objectionable, as 20 none have been devised that are sufficiently powerful to be effective, owing to the cramped room between the piston rod and the wristpin hole, necessitating accompanying effort such as driving the cross-head with 25 a heavy sledge hammer and other auxiliary efforts requiring often four and five hours' time and sometimes one and one-half days to remove one piston rod.

A further objectionable result of employing 30 the wristpin hole of the cross-head for removing piston rods is the cracking and breaking of the cross-head resulting further in the total loss of the cross-head.

A still further result of employing the 35 wristpin hole, is the cracking or rupture of the cross-head that is not detected at the time, the engine going out and the cross-head breaking while the engine is running, always resulting in breaking the companion 40 cylinder and sometimes causing a wreck of the train.

The present invention has provided an improved piston kicker with a powerful hydraulic cylinder that is attached to the 45 cross-head and the piston rod removed in a few minutes with no possible resulting injury to the cross-head or piston rod.

By employing the improved piston kicker a great saving of time is effected and abso-

lute elimination of breakage, injury and 50 wrecks from employing piston kickers is attained.

With these and other objects accomplished the invention consists in the features of construction, combinations and arrangements of 55 parts as hereinafter set forth, and more particularly pointed out in the appended claims, the accompanying drawings illustrating a form of the improved piston kickers that has proven more than satisfactory. 60

In the drawings:

Fig. 1 is a fragmentary view in side elevation of a locomotive and of the improved piston kicker.

Fig. 2 is an inverted plan view of Fig. 1. 65

Fig. 3 is a sectional view on line 3—3 of Fig. 1, also illustrating a very desirable method of placing the piston kicker in working position.

Fig. 4 is a fragmentary end view of the 70 piston kicker illustrating the reverse position of the pump handle for the opposite side of the engine from that shown in Fig. 1.

Fig. 5 is a fragmentary sectional view taken on line 5—5 of Fig. 1. 75

Fig. 6 is a plan view of the hydraulic cylinder of the piston kicker and the truck employed for placing it in working position, also illustrating certain parts of the kicker loaded on the truck for moving from one 80 locomotive to another.

Fig. 7 is an enlarged sectional view of the 85 hydraulic cylinder taken on line 7—7 of Fig. 6, and showing the plunger rod and other small parts in full view.

The cylinder 1 shown in fragmentary view, the piston rod 2, cross-head 3, bottom guide bar 4, top guide bar 5, guide yoke 6 and step 7 are all of usual and common construction, shown merely to illustrate the use 90 of the piston kicker.

The cylinder 8 is of a considerably larger diameter than could be inserted within the cross-head 3 or between the wristpin bosses 9 thereof, so that sufficient force may be 95 exerted to remove the piston rod 2 immediately when the force is applied.

It will be understood that the cylinder end

of a locomotive is commonly called the front end and that the terms front and rear are applied to all parts in conformity to this rule.

5 The cylinder 8 being larger than the internal dimensions of the cross-head, it is for the purpose of the present invention located to the rear of the cross-head as shown and provided with the lugs 10 into which are 10 engaged the hook bolts 11, the bolts extending upwardly and through the cross bars 12 which rest on the upper guide bar 5. It will be understood from the foregoing that the cylinder 8 is suspended from the guide 15 bar 5 by the bolts 11 and that it may be adjusted to the desired height by the bolts.

The cylinder 8 is provided with the laterally extending lugs 13 forming bifurcated jaws into which the bolts 14 rest, the bolts 20 extending on either side of the cross-head 3 and to the opposite end thereof and passing between the clamp bars 15 and through the washer plates 16 so that the bolts secure the cylinder rigidly to the cross-head at any de- 25 sired distance therefrom, the distance being regulated by the bolts 14.

The cylinder 8 is provided with the working plunger 17, pressure cup 18, plunger rod 19, drip hole 20, pressure pump 21, release 30 cock 22, release spring 23 and the end 24 of the plunger rod is provided with the projecting center 25 to engage the usual hollow center in the end of the piston rod 2 and maintain the end of the plunger rod con- 35 centrically with the end of the piston rod.

The pump is actuated by the lever 26 fulcrumed on the bracket 27, which is secured to the cylinder 8 by the stud bolts 28 and 29. In the views Figs. 1, 2, 3 and 6 the bracket 40 27 is secured to the cylinder 8 by the stud bolt 28, while in Fig. 4 it is secured to the cylinder by the stud bolt 29, this being the means by which the lever is reversed in order to operate on either side of the locomotive, 45 there is no change of parts, merely a reverse position.

In Fig. 3 the truck 30 is shown in the position by which the piston kicker is placed in working position and removed therefrom, the 50 truck being constructed as shown so as to reach over the usual step 7.

In Fig. 6 is shown a plan view of the truck 30 with certain parts of the piston kicker loaded thereon as moved from place to place, 55 it being understood that all the parts may be loaded on the truck.

When it is desired to remove a piston rod from the crosshead of a locomotive, the cylinder 8 is placed as shown in Figs. 1, 2 and 3, 60 with the truck 30 or otherwise and the hook bolts 11 and cross bars 12 attached so as to suspend the cylinder at the desired height with the projecting center 25 resting in the usual hollow center in the end of the piston rod 2. The bolts 14, clamp bars 15 and

washers 16 are then placed and the plunger rod 19 held against the piston rod by the bolts. The release cock 22 is closed and water or other liquid as thin oil supplied to the pump 21 by the pipe 31 and the pump 70 operated by the handle 26. It will be understood that a great force is exerted on the working plunger 17 and plunger rod 19 and on the piston rod 2, the piston rod being immediately removed from the cross-head 3. 75 The pull of the cylinder is through the bolt 14 and clamp bars 15 and against the projecting bossed front end 32 of the cross-head so that no possible injury can result to the cross-head, whereas by pulling on the rear 80 wall of the wristpin hole 33 by wedges, screws and hydraulic cylinders that engage this hole, cross-heads are frequently broken and one and one-half days are sometimes consumed in removing the piston rod. 85

When the piston rod has been removed the release cock 22 is opened and the release spring 23 returns the plunger to approximately the position shown in Fig. 7, the liquid passing out through the release cock. 90

The improved piston kicker performs a work immediately for which there has been no practical means heretofore known and will eliminate the destruction of many cross-heads on a single railway in one year and 95 an occasional train wreck.

Having described my invention, what I claim as new and desire to secure by Letters Patent, is:—

1. In a piston kicker for removing piston rods from the cross-heads of locomotives, a pair of supporting bars adapted to rest transversely upon the guide bar of a locomotive, a cylinder, a plunger in said cylinder, a plunger rod projecting from said plunger 105 and said cylinder, a plurality of bolts detachably engageable with said cylinder whereby said cylinder can be suspended rearwardly of the cross-head from said supporting bars, said plunger rod adapted to bear against the piston rod when said cylinder is so suspended, a pair of clamp bars adapted to be positioned on opposite sides of the piston rod and bear against the front end of the cross-head adjacent the piston rod, bolts 115 to connect said clamp bars and said cylinder, and a pump connected to said cylinder.

2. In a piston kicker for removing piston rods from the cross-heads of locomotives, a cylinder, means to suspend said cylinder from the guide bar of a locomotive in a position adjacent one end of the cross-head, means to connect said cylinder immediately around the piston rod to the opposite end of the cross-head, a plunger rod projecting 125 from said cylinder and provided with a projecting center to engage the usual hollow center in the end of the piston-rod and retain said plunger concentric with the piston rod, and a pump arranged to force liquid 130

into said cylinder and project said plunger rod further out of said cylinder.

3. In a piston kicker for removing piston rods from the cross-head of locomotives, a portable cylinder, a portable means to operatively position said cylinder adjacent one end of the cross-head of a locomotive and to receive said cylinder when detached from the

locomotive, means to connect said cylinder to the opposite end of the cross-head immediately adjacent the piston rod, a plunger rod projecting from said cylinder to engage the end of the piston rod, and a pump connected to said cylinder. 10

EVERET HOLLOWELL.
